JOSEPH D. COUGHLIN, OF NEW YORK, N. Y.

WARNING SIGNAL.

1,408,346.

Specification of Letter Patent. Patented Feb. 28, 1922.

Application filed April 20, 1921. Serial No. 462,955.

To all whom it may concern:

Be it known that I, JOSEPH D. COUGHLIN, a citizen of the United States, and a resident of the city of New York, borough of Manhattan, in the county and State of New York, have invented a new and Improved Warning Signal, of which the following is a description.

My invention relates to warning signals such as used on automobiles and other vehicles and more particularly to the type of signal involving a vibratable diaphragm and a rotary vibrator adapted to be actuated by an axially movable operating device.

15 An object of my invention is to provide a signal of the indicated type having a diaphragm and a vibrator so formed and relatively arranged as to overcome the startling and disagreeable sounds produced by the usual signal, this object being attained by a contact element on the diaphragm yieldable in itself in addition to partaking of the vibrations of the diaphragm, and by providing for wiping action by the vibrator instead 25 of a clashing engagement.

A further important object of the invention is to provide a signal of the type referred to that may be operated gently and with the minimum expenditure of force.

30 An object of the invention also is to provide a signal of the indicated type, involving elements of the simplest form and few in number, so that the signal is in such compact construction and involves so low a cost 35 of production as to adapt it to a wide field of usefulness, including its use on bicycles.

Reference is to be had to the accompanying drawings forming a part of this specification, it being understood that the drawings 40 are merely illustrative of one example of the invention.

Figure 1 is a sectional side elevation of a warning signal embodying my invention;

45 Figure 2 is a horizontal section taken above and adjacent to the rotary vibrator;

Figure 3 is a rear face view of the diaphragm;

Figure 4 is a central horizontal section of the diaphragm;

50 Figure 5 is a perspective view of the actuating element for imparting movement to the vibrator;

Figure 6 is a perspective view of the operatively engaged portion of the vibrator;

Figure 7 is a horizontal section on the line 7—7, Figure 1, but with the tubular operating element depressed.

In carrying out my invention in accordance with the illustrated example a shell 10 is provided, closed at the rear end 10^a and in practice produced from a single piece. Across the open front end of the shell 10 is a diaphragm 16 disposed in front of an annular flange 12 on the shell 10 between said flange and a clamp ring 13 of suitable cross section 65 which is secured in place by bolts 14, or equivalent fasteners passing through said clamp ring, through the flange 12, and through an interposed packing ring 15.

The diaphragm 16 is provided with bolt 70 holes to be clamped by the clamping of the ring 13, as usual. I provide on the diaphragm 16 a novel contact element 16^a. Said contact element is flat and as here shown is formed of a separate piece of metal, soldered, brazed, or otherwise secured centrally to the diaphragm. One end of the contact element 16^a is disposed at an angle to the plane of the diaphragm. The free end of the contact element 16^a is resilient.

I provide a novel vibrator 17 for engaging the contact element 16^a. Said vibrator advantageously is generally of cup-shape and mounted to turn on an axis parallel with the diaphragm 16 as hereinafter referred to. 85 On the upper edge of the cup-shaped diaphragm 17 are upstanding fingers 17^a turning in a path that will present lateral surfaces thereof in succession to the opposed flat surface of the contact element 16^a to 90 wipe over said contact element flexing the same and vibrating the diaphragm 16. The wiping of the lateral surfaces of the fingers 17^a over the flat contact element 16^a results in a smaller jump from one finger to the 95 other in the successive contacting of the element 16^a therewith, and a clashing sound by the fingers in the successive engagement of the fingers is avoided. The yielding of the contact element also, coupled with the side 100 engagement of the vibrating fingers, requires less force to cause the vibrator to revolve than when the ends of teeth or like elements are engaged with an unyielding contact element on a diaphragm.

The vibrator 17 has a central boss 18 formed with a lateral flange 18^a at the top, said flange having a tooth 19 to be engaged

- by the actuating device as will appear, said tooth being usually in practice struck up from the flange 18^a and formed to give it essentially the character of a ratchet tooth.
- 5 A cut-out 18^d results from the stamping up of the tooth 19 and it may be partially compensated for by balancing the vibrator, by producing another cut-out or recess 18^e diametrically opposite in the flange 18^a.
- 10 The vibrator 17 is disposed horizontally so as to turn about a vertical axis and bearing means is provided at the under side of the vibrator consisting preferably of a vertical pin 20 rising in the shell 10 at the bottom said vibrator 10 having a vertical blind bore 18^d extending from the under side thereof at the boss 18. As shown, the pin 20 has an enlarged threaded zone 20^a to engage in an internally threaded boss 10^b produced on the shell 10 at the interior. The head of the pin 20 is slotted to take a screw driver.

For revolving the vibrator 17 I provide a spiral actuating device 23 having a clutch head 24 thereon at its lower end, said head presenting a plurality of clutch arms 25, there being four in the present example adapted to engage the tooth 19 when said actuating element is turned. Below the clutch head 24 the actuating device 23 is formed with an integral centering pin 26 adapted to enter a centering and bearing bore 27 (Fig. 6) in the upper end of the boss 18. The operating means for the actuating device 23 is as follows: The spiral shank of said actuating device is disposed in a tubular fixed element 29, the external threads of which engage an internally threaded boss 30 formed at the interior of the shell 10 at the top, the upper end of the tube 29 protruding through the top of the shell and having a nut 31 thereon. Telescoping in the tube 29 is an operating tubular element 32 having at one side thereof a laterally projecting key 33 slidable in a longitudinal slot 34 of tube 29 to prevent turning of the operating tube and cause it to have a direct up-and-down movement in the tube 29. The upper end of the spiral actuating element 23 extends through a transverse slot 35 in the end 36 of the element 32. The operating element 32 has a broadened head 37 preferably of inverted cup-shape and a spring 38 coiled about said tube serves to lift 55 the tube after the pressure thereof.

On the lower end of the tube 29 is an enlarged housing 39 having a radial flange 40 directed laterally inward and internally threaded to engage adjustably the threaded exterior of said tube 29. The housing 39 has a diameter to permit vertical play of the clutch head 24 and it has the important function also that it may be adjusted on the tube 29 to lie close to the vibrator 17 with-

out frictionally engaging the latter but preventing displacement of the vibrator.

With the described construction, upon the element 32 being caused to move downwardly in the tube 29, by a pressure on the head 37, the engagement of the spiral element 23 in the slot 35 will cause said element 23 to be given a turning movement so that an arm 25 of clutch head 24 will engage the tooth 19 of vibrator 17 thereby revolving the latter and causing the fingers 17^a to wipe over the resilient contact element 16^a of the diaphragm 16. In practice the vibrator 17 has sufficient mass to continue turning under its own momentum after the manner of a flywheel upon an impulse being imparted thereto by the actuating element 23. Thus, the vibrator runs ahead of the actuating element 23 and in doing so the bevelled back surface of the ratchet tooth 19 will engage a bevelled surface 25^a of an arm 25 permitting the clutch head 24 to ride over said tooth. The riding of clutch head 24 over tooth 19, and the frictional engagement between the spiral actuating device 23 and operating element 32 when the latter is raised, will cause said device 23 and its clutch head 24 to rise in the tube 29 and dispose the clutch head 24 above the plane of the tooth 19 to permit the free turning of the vibrator 17 under its own momentum.

The manner of mounting the rotary vibrator 17 solely on a bearing pin at the under side thereof makes the vibrator sensitively responsive to the actuating device 23 and the vibrator is revolvably sustained independent of the actuating and operating means.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim:

1. In a signal of the class described, a diaphragm having a contact element thereon resilient in itself in addition to partaking of the vibrations of the diaphragm; together with a cup-shaped vibrator having contact members projecting from the edge of the vibrator approximately parallel with the axis of said vibrator, the side surfaces of which are adapted to wipe successively over the contact element of the diaphragm.

2. In a signal of the class described, a diaphragm having a flat contact element thereon, and a revolvble cup shaped vibrator turning about an axis parallel with the diaphragm and having contact fingers projecting from the edge of said vibrator paral-

lel with the diaphragm, and separated from each other by open spaces, said fingers presenting lateral faces to said contact element and adapted to wipe over the same in succession.

3. In a signal of the class described, a diaphragm, a vibrator mounted to turn about an axis substantially parallel with the diaphragm, a spiral actuating element, said element and vibrator having coacting engaging members, the vibrator being adapted to run ahead of the actuating element under its own momentum, a tube in which said spiral element may rise, free from the diaphragm and a depressible tubular operating element telescoping in said tube and presenting a transverse slot in its lower end through which the spiral actuating element extends.

4. A signal of the class described including a vibratable diaphragm, a revoluble vibrator therefor, a spiral actuating device for the vibrator, said device and said vibrator having co-engaging means and the vibrator being adapted to turn independently under its own momentum, a tube in which said actuating device may rise, and a reciprocating tubular operating device telescoping in

said tube and having a transverse slot receiving the spiral actuating device.

5. A signal of the class described including a diaphragm, a revoluble vibrator therefor, an actuating device for said vibrator, a tube in which said actuating device operates, said tube having a member thereon adjustable relatively to the vibrating device to lie adjacent to the latter and guard against displacement thereof.

6. A signal of the class described including a diaphragm, a rotary vibrator therefor, and actuating means for the vibrator, said vibrator turning about an axis substantially parallel with the plane of the diaphragm and having bearing means solely at the under side thereof.

7. A signal of the class described including a diaphragm, a rotary vibrator therefor, and actuating means for the vibrator, said vibrator turning about an axis substantially parallel with the plane of the diaphragm and having bearing means solely at the under side thereof; together with an element lying adjacent to the top of the vibrator to guard against displacement thereof.

JOSEPH D. COUGHLIN.
